(57) **CLAIM**

The ornamental design for a hood top, as shown and described.

DESCRIPTION

FIG. 1 is a perspective view of a hood top according to our new design;

FIG. 2 is top view of the hood top of FIG. 1;

FIG. 3 is a front view of the hood top of FIG. 1;

FIG. 4 is a left side elevational view of the hood top of FIG. 1; and,

FIG. 5 is a right side elevational view of the hood top of FIG. 1.

The broken lines immediately adjacent the shaded areas, including those disposed around a portion of the periphery of the design as depicted in the FIGURES, represent the bounds of the claimed design while all other broken lines are directed to environment and are for illustrative purposes only; the broken lines form no part of the claimed design.
